UNITED STATES PATENT OFFICE.

JOSEPH PETERMANN, OF PHILADELPHIA, PENNSYLVANIA.

TRENCH-CUTTER.

1,321,770.

Specification of Letters Patent.

Patented Nov. 11, 1919.

Application filed July 12, 1919. Serial No. 310,309.

To all whom it may concern:

Be it known that I, JOSEPH PETERMANN, a citizen of the United States, residing at Philadelphia, in the county of Philadelphia and State of Pennsylvania, have invented 5 new and useful Improvements in Trench-Cutters, of which the following is a specification.

This invention relates to machines for 10 cutting and breaking up earth, rock and other hard substances such as are usually encountered when excavating or cutting trenches, tunnels and the like in the ground for road making, sewer and conduit laying, 15 or when boring for tunnels, shafts, and so forth.

The main object of this invention is to provide a machine for the purposes above referred to wherein the hammer, drill or 20 other tool is so disposed that the full weight and pressure of the hammer, drill or other tool is always directly in line with the blow so that said tool gives the fullest resistance to the work.

25 Another object of this invention is to provide a trench cutter in which the engine, compressor and tool are combined and carried by a single truck whereby greater efficiency is attained and considerable manual labor saved.

30 A further object is to provide a trench cutter in which the tool is so mounted relative to the truck body that it may be operated in any direction without in any way detracting from its efficiency or impeding 35 its proper operation.

With these and other objects in view, as 40 will later be more apparent, my invention consists essentially in the novel features of construction, combination and arrangement of parts hereinafter fully described and more specifically pointed out by the appended claims.

In the further disclosure of the invention, 45 reference is to be had to the accompanying drawings, constituting a part of this specification, in which similar characters of reference denote corresponding parts in all the views, and in which:

50 Figure 1—is a plan view of a trench cutter embodying my improvements.

Fig. 2—is a side elevation of the same.

Fig. 3—is an enlarged fragmentary side elevation of the cutting tool supporting 55 mechanism, associated parts, and the rear end of the truck frame.

Fig. 4—is an end elevation of the same, and looking from the left hand of the preceding figure.

Fig. 5—is a top plan view of the same. 60

Fig. 6—is an enlarged longitudinal section of the tool support proper.

Fig. 7—is a section on the line 7—7 in the preceding figure and looking in the direction of the arrows. 65

Fig. 8—is a section on the line 8—8 in Fig. 6; and

Fig. 9—is a perspective view of a detail hereinafter more specifically referred to.

Referring to the drawings, the truck 70 proper α includes opposed spaced side members 10, 10, preferably made of strong channel irons, which are braced together by cross beams 11, 11, similarly made of channel sections and securely bonded to the 75 side members by angles 12, 12. This truck frame or body α , has securely fixed to each side thereof by bolts 13, heavy V-shaped bearing members 14, which are cut away in vertical section to seat beneath the channels 80 10, 10, and in these bearing members 14, are fitted in any of the well known ways the axles 15, for the road wheels 16, 16', it being of course understood that a fifth wheel 17, is provided in connection with the front 85 axle 15, so that the truck can be properly handled when moved from place to place.

Mounted on an appropriate platform carried by the truck α are the compressor 18, and engine 19, which are of any of the 90 standard types.

At or near the rear end of the truck α , and at each side thereof I mount opposed bearing members 20, 20, which are undercut or recessed at 21, to fit snugly on the side members 10, and to which they are securely held by bolts 22. These bearing members 20, 20, 95 constitute pedestals or supports for a transverse shaft 23, which seats in the ends thereof at 24, and is prevented from rotation by 100 set screws 25. Fitting snugly to the bearing members 20, 20, are vertically disposed channels 26, in the upper ends whereof are secured bearing bushes 27, held in place by set screws 28. Spaced from the aforesaid 105 bearing members 20, 20, are corresponding members 29, 29, which constitute pedestals or supports for a transverse shaft 30, which seats in the ends thereof at 31, and is prevented from rotation by set screws 32, bolts 110 33, holding the members 29, 29, in place.

Slidably mounted on the shafts 23, 30, are

a pair of heavy cranked members 34 which are kept in proper spaced relation by angle ties 35, one flange whereof is embedded therein at 36, and said angles are locked in place by screws 37. These cranked members 34, are bored at their elbows 38, to receive a tubular shaft 39, which is prevented from rotation by opposed keys 40, and a locking stud 41, and in the ends of said tubular shaft 10 I form opposed longitudinal cut-away portions 42, Fig. 7—in which snugly fit the fantail projections 43 of internally threaded nuts or sleeves 44—Fig. 9. Collars 45, snugly fit the ends of the shaft 39, and are 15 held firmly in place by set screws 46. Passing axially through the hollow shaft 39, and in threaded engagement with the aforesaid nuts 44, is a transverse screw shaft 47, the reduced ends 48, whereof are housed in 20 the bearings 27 hereinbefore referred to, and keyed or otherwise attached on the outer ends are hand-wheels 49. Thus it will be seen that by manipulating the hand-wheels 49, the spaced members 34, and hollow shaft 25 39, can be traversed from side to side of the machine.

Fitting snugly on the shaft 39, are a pair of clamping jaws 50, fashioned at one side with semi-circular dovetail jaws 51, in which 30 snugly and revolvably fits the conical projection or nut 52, of the hammer or drill shell 53, which is supplied with compressed air from the compressor 18, in any of the well known ways. Clamping or locking means 35 of any of the well known forms may be provided for holding the tool in any desired position.

From the foregoing description it will be 40 readily seen that by my invention I provide an effective and reliable machine for the purposes specified in which the tool can be operated in any vertical or angular direction relative to the longitudinal axis or transversely of the truck. Furthermore by 45 connecting the engine 19, through a chain drive 54, with a sprocket wheel 55, on the rear axle 15, and fitting a steering mechanism 56, in connection with the fifth wheel 17, the entire machine is rendered self propelled.

Still further it will be readily understood 50 that by my invention I provide a trench-cutter or hammer which is self-propelled and in which the hammer or cutting tool can be operated at any angle while still having the full weight or pressure of the hammer to give full resistance to the impact of said hammer. Further the hammer or tool can be moved from side to side or up and 60 down at any angle without cutting-off the motive power thereto whereby a great saving of time is effected, and economy in labor ensues. It will also be seen that I have the full weight of the hammer, 65 compressor and engine directed to resist the im-

pact of the blow or cut inasmuch as they are all closely related on the truck body while by substituting a drop hammer the machine can be employed for crushing stone, concrete or similar hard or homogeneous 70 substances.

Finally it will be readily acknowledged that by my present improvements, I provide an exceedingly effective and powerful machine for the purposes specified as well as 75 an easy and efficient means for manipulating the same, and I wish it understood that while I have described one specific embodiment of my invention in detail, I do not confine myself rigidly thereto, as it is obvious that slight changes may be made in the particular arrangement and combination of the several parts, without departing from the nature and essential features of my said invention. For instance, I do not 80 restrict myself to the employment of channel irons, but consider myself at liberty to employ other appropriate sections to adapt my invention to particular working conditions.

Having described my invention what I claim as new and desire to secure by Letters Patent is:—

1. In a machine of the type described, the combination with the truck body, engine 95 and compressor, of spaced bearing members mounted on said truck body, shafts mounted in said bearing members, spaced bearing members slidably mounted on said shafts and supporting a hollow shaft, a screw axially disposed in said hollow shaft and having threaded engagement with the ends thereof, clamping means carried by the hollow shaft and having a swivel head on which the tool is mounted, and means for 100 rotating the screw to traverse the tool from side to side of the machine.

2. In a machine of the type described, the combination with the truck body, engine and compressor, of spaced bearing members 110 mounted on each side of the truck body, transverse shafts mounted in said bearing members, cranked members slidably mounted on said shafts and supporting a hollow shaft, a screw axially disposed in said hollow shaft 115 and having threaded engagement with the ends thereof, clamping means carried on the hollow shaft and having a swivel head for supporting the tool, and means for rotating the screw to traverse the tool from side 120 to side of the machine.

3. In a machine of the type described, the combination with the truck body, engine and compressor, of spaced bearing members mounted on each side of the truck body and 125 having recessed parts to fit snugly on the side members thereof, transverse shafts rigidly mounted in the said bearing members, cranked members slidably mounted on said transverse shafts and connected in spaced 130

relation, a hollow shaft rigidly secured in the elbow portions of the cranked members, a screw axially disposed in said hollow shaft and having threaded engagement with 5 winged sleeves secured in the ends thereof, clamping jaws carried by the hollow shaft and having a swivel head for supporting the tool, and means for rotating the screw to traverse the tool from side to side of the 10 machine.

4. In a machine of the type described, the combination with the truck body, engine and compressor, of spaced bearing members having recessed parts to fit snugly on the 15 side members of the truck body, transverse shafts rigidly mounted in said bearing members, cranked members, slidably mounted on the transverse shafts and connected in spaced relation by partially inset angle ties, a hollow shaft rigidly secured in the elbow portions of the cranked members, a screw axially disposed in the hollow shaft and having threaded engagement with winged 20 inserts secured in and locked to the ends thereof, and the end of said screw being freely 25 revoluble in bearings extending upwardly

from the opposed rear bearing members, clamping jaws carried by the hollow shaft and having a swivel head for supporting the tool, and means for rotating the screw 30 to traverse the tool from side to side of the machine.

5. A machine of the type described comprising in combination, a truck body having road wheels, an engine and compressor 35 mounted on the truck body, said engine being adapted to drive the compressor as well as propel the truck when desired, spaced bearing members mounted on the truck body, shafts mounted in said bearing members, cranked members slidably mounted on said shafts and supporting a hollow shaft, a screw axially disposed in said hollow shaft and having threaded engagement with the ends thereof, clamping jaws carried by the 40 hollow shaft and having a swivel head on which the tool is mounted, and means for rotating the screw to traverse the tool from side to side of the machine.

In testimony whereof I affix my signature. 45

JOSEPH PETERMANN.
